UNITED STATES PATENT OFFICE.

GUNNAR O. LILJEGREN, OF ST. LOUIS, MISSOURI.

AUTOMATIC FIRE-EXTINGUISHER.

1,172,469.

Specification of Letters Patent. Patented Feb. 22, 1916.

Application filed September 1, 1915. Serial No. 48,561.

To all whom it may concern:

Be it known that I, GUNNAR O. LILJEGREN, a citizen of the United States, residing at the city of St. Louis and State of 5 Missouri, have invented a new and useful Automatic Fire-Extinguisher, of which the following is a specification.

This invention relates to automatic fire extinguishers.

10 An object of the invention is to provide an improved automatic fire extinguisher having a strut composed of two coacting levers mounted in position to hold the closure in connection with the nozzle and provided with an improved link of novel construction for holding the lever in proper adjustment so that, when the fusible material of the link becomes fused, the pressure of the water within the nozzle will 15 cause the levers to separate the link members and permit the closure to be forced away by the water coming out of the nozzle.

Another object of the invention is to provide a device of the class mentioned comprising a link of novel construction and consisting of two end pieces which are connected to the levers and which engage with an intermediate or central piece which is free of the levers, and solder placed upon 20 the angular engaging portions of the several pieces to hold them in assembled relation and arranged so that when the solder is fused the pressure of the levers will throw the three pieces apart and permit the water 25 to come out of the nozzle.

In the accompanying drawings, in which I have illustrated a preferred embodiment of the invention, Figure 1 is a sectional view of the device. Fig. 2 is a side elevation. 40 Fig. 3 is a perspective view of one of the end pieces of the link by which the two coacting levers are held together. Fig. 4 is a perspective view of the middle or central portion of the link. Fig. 5 is a perspective 45 view of the other end portion of the link.

The nozzle 1 is exteriorly threaded so that it may be readily connected with the water pipe upon which it is to be mounted. A yoke or frame 2 is in connection with the 50 nozzle and supports an adjusting screw 3 which is in axial alinement with the axis of

the nozzle. The adjusting screw passes through the outer portion of the yoke or frame 2 and binds in place the distributing plate 4 by which the water, coming out of 55 the nozzle, is sprayed or distributed over a considerable area. The inner extremity 5 of the screw 3 is pointed so as to provide a more efficient contact point for the lever. The closure 6 is adapted to close the opening from the nozzle and is formed with an attenuated projection 7 in alinement with the point 5 of the screw 3.

An outer lever 8, which is angular in side elevation, has a recess in the end of one of 65 its arms receiving the pointed extremity 5 of the screw 3 which constitutes an abutment or bearing for said lever. The angle of the lever 8 is formed with a bearing portion 9 which abuts against a bearing portion 10 of an inner angular lever 11. The end of one of the arms of the lever 11 bears against the attenuated portion 7 of the closure 6 and the two levers are mounted in substantially the same vertical plane and are 70 of substantially the same length. The outer portions of the levers 8 and 11 diverge from each other and each of said levers is provided with a hook 12 at its outer extremity.

From the foregoing description and by 80 reference to Fig. 1, it will be understood that the contacting or abutting points 9 and 10 of the two levers 8 and 11 are laterally from an axial line passing through the screw 3 and the nozzle 1 so that the pressure 85 of the water within the nozzle tends to separate the two levers, thus requiring the provision of a connection for holding the two levers together and which will yield to the influence of heat of a predetermined temperature to permit the two levers to separate 90 so that the water may come out of the nozzle. This connecting device between the ends of the levers is of novel construction and I will now describe the same.

95 The connecting device or link is composed of three co-operating members or pieces. The member or piece 13 is in the form of a plate having an opening or passage 14 for receiving the hook 12 of one of the levers 8 100 or 11. At each side of the opening or passage 14 of the plate 13 is provided with pro-

jections or flanges 15 which may be formed by turning or bending the edge portions of the plate. The opposite edge of the plate is provided with a laterally extending flange 5 or projection 16 which may also be formed by bending or turning the edge portion of the plate.

The opposite end member or piece of the link consists of a plate 17 having an opening or passage 18 for receiving the hook 12 of one of the levers 8 or 11. The plate 17 is also provided with laterally extending projections or hooks 19, similar to the projections 15 and are formed by bending or 10 turning the edges of the plate 17 at the sides of the passage or opening 18. The edge of the plate 17, opposite from the hooks or projections 19, is provided with the laterally extending flange or projection 20, similar 15 to the flange or projection 16 and formed by bending or turning the edge portion of the plate.

By reference to Fig. 1 it will be observed that the combined length of the plates 13 25 and 17 is somewhat greater than the distance between the ends of the levers 8 and 11 so that, when said plates are placed upon the levers, the flange or projection 20 of the lower plate 17 is above the plane of the 30 flange or projection 16 of the upper plate 13.

The central or intermediate member or piece of the connecting link is angular in 35 formation and the construction thereof will be understood by reference to Figs. 1 and 4. By reference to these views of the drawing, it will be seen that the central member includes the upper portion 21 adapted to bear against the face of the plate 13 and the lower portion 22 adapted to bear against 40 the face of the plate 17, and a substantially horizontal portion 23 constituting a connection between the upper and lower portions 21 and 22 and adapted to be engaged by the flanges or projections 16 and 20 of the upper 45 and lower portions of the connection. Thus, by reference to Fig. 1, it will be understood that the flange or projection 16 engages under the shouldered connection 23, while the flange or projection 20 engages over said 50 shouldered connection. This arrangement holds the three pieces of the link in oblique planes with respect to the axis of the nozzle so that, when the fusible material bonding together the three pieces of the link becomes 55 broken or fused, the pressure of the levers 8 and 11 upon the different portions of the link will readily separate them.

The upper and lower edges of the plate 21-22 are below and above the flanges 15 60 and 19 respectively, so that they will not become engaged therewith, but will be free to spread apart when the fusible solder permits. Said projections, however, constitute engaging portions for the solder as will be

understood by reference to Fig. 1, so that the 65 solder cannot be broken by the pressure of the levers. It will be seen that the upper portion 24 of the solder engages under the flanges or projections 15 and is securely and firmly bonded therewith and with the face 70 of the upper portion 21 of the intermediate member of the link. The solder 24 also engages and holds the flange or projection 20 upon and in connection with the shouldered connection 23 of the intermediate member 75 of the link. Similarly the lower mass 25 of solder engages with the flanges or projections 19 and with the face of the lower portion 22 of the intermediate member and also engages the flange 16 of the upper plate 13 80 holding the same under and in connection with the shouldered connection 23 of the intermediate member of the link. The solder placed in this way forms a strong bond between the different members of the link 85 which, being mounted in the oblique positions described and illustrated, readily separate or spread under the pressure of the levers so that, when the solder becomes fused, the nozzle is quickly opened. 90

The advantages of a device embodying these principles and features of construction are obvious. It will be understood that I do not confine myself to specific features of construction, except where such features are 95 included within the appended claims.

What I claim and desire to secure by Letters Patent of the United States, is:—

1. In an automatic fire extinguisher, a fusible link comprising two duplicate and interchangeable end plates each having a hole near its outer extremity, a flange extending across the inner edge of each plate, an intermediate member having a shoulder engaging the flanges at the inner edges of said plates and having upper and lower portions bearing against the surfaces of said plates, flanges at the sides of said holes on the same side with said first-named flanges extending across the plane of said intermediate member and fusible solder engaging said flanges and said shoulder and the ends of said member to bind said parts together. 100

2. In an automatic fire extinguisher, a fusible link comprising two end plates adapted to engage with the strut levers, lateral flanges adjacent to the outer end of each plate, a lateral flange at the inner end of each plate on the same side thereof with the first-named flanges, an intermediate member having upper and lower portions bearing against the side surfaces of said plates and having a shouldered connection engaging with the flanges at the inner ends of said plates, the outer ends of said intermediate member being beyond the inner ends of said plates and a sufficient distance from the flanges near the outer ends of said plates to 115 120 125

permit said intermediate member to move free of said flanges, and fusible solder engaging said flanges and the outer portions of said intermediate member and also engaging said shoulder connection effectively to bind said parts together.

5 In witness whereof, I have signed this

specification in the presence of two subscribing witnesses.

GUNNAR O. LILJEGREN.
